CLAIM

The ornamental design for laptop, as shown and described.

DESCRIPTION

FIG. 1 is a front perspective view of a laptop in a closed position, showing my new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view of the laptop in an open position;

FIG. 10 is an enlarged view taken from FIG. 9;

FIG. 11 is an enlarged view taken from FIG. 9; and,

FIG. 12 is an enlarged view taken from FIG. 9.

The dashed broken lines in drawings show portions of the laptop that form no part of the claimed design. The dotted lines in FIGS. 9-12 illustrate boundaries between claimed and unclaimed subject matter, and form no part of the claimed design. The dot-dash lines in FIGS. 9-12 and the dot-dash lead lines labeled “10”, “11” and “12” respectively show the areas from which the enlargements in FIG. 9 are taken and form no part of the claimed design.
